The ornamental design for a storage display, as shown and described.

DESCRIPTION

FIG. 1 is a perspective view of my new design for a storage display unit;

FIG. 2 is a typical elevational view from one side of the storage display of FIG. 1, showing the end view of the upper support beam for the wheel assembly cross-beam tier;

FIG. 3 is a typical elevational view from one side of the storage display of FIG. 1, that is a forty-five (45) degree rotation of the storage display shown in FIG. 2, showing the end view of the lower support beam for the wheel cross-beam tier;

FIG. 4 is a top plan view of the design for the storage display shown in FIG. 1; and,

FIG. 5 is a bottom plan view of the design for the storage display shown in FIG. 1.
